CLAIM

The ornamental design for a combined rocker box handle and rocker arm positioner, as shown and described.

DESCRIPTION

FIG. 1 is a perspective view of a combined rocker box handle and rocker arm positioner, showing my new design;

FIG. 2 is a top plan view thereof;

FIG. 3 is a front elevational view thereof;

FIG. 4 is a bottom plan view thereof;

FIG. 5 is a rear elevational view thereof; and,

FIG. 6 is an elevational view of one end, the opposite end being a mirror image thereof.
